W. P. ALEXANDER

SKIP HOIST SYSTEM

Filed Oct. 13, 1924

WITNESS:

Robt. R. Kitchel.

INVENTOR

William P. Alexander
BY

Augustus B. Stoughton
ATTORNEY.

UNITED STATES PATENT OFFICE.

WILLIAM P. ALEXANDER, OF MERCHANTVILLE, NEW JERSEY, ASSIGNOR TO R. H. BEAUMONT COMPANY, INC., OF PHILADELPHIA, PENNSYLVANIA, A CORPORATION OF PENNSYLVANIA.

SKIP-HOIST SYSTEM.

Application filed October 13, 1924. Serial No. 743,278.

Objects of the present invention are to provide for the simultaneous operation of the buckets of two skip hoists from a single driving unit for both skip hoists; to economically apply the power; to simultaneously operate the buckets of two skip hoists, one from a low to an intermediate level, and the other from the intermediate level to a high level with economy in both installation or structure and power application; to increase the capacity, if desired, by increase in the number of trips without undue increase in cable speed and without additional bucket capacity; to accomplish any or all of the foregoing objects while retaining the advantages due to counterweighting or balancing the ascending and descending buckets and cables; and to provide a skip hoist system economical both in respect to installation cost and operating expense and adapted to lift, for example, coal from a comparatively shallow pit to some storage or processing plant or station supported substantially at the ground level which is the intermediate level and to further lift material from the plant or processing station to a high level for distribution or use.

The invention comprises the improvements to be presently described and finally claimed.

In the following description reference will be made to the single figure in the drawings which is a diagrammatic or schematic illustration of one embodiment of the invention selected from other embodiments for the sake of explanation.

The embodiment of the invention illustrated in the accompanying drawing is well adapted for receiving coal, delivering it to and from a crusher plant, and lifting the powdered or pulverized coal for distribution or use, but it must be borne in mind that the invention is by no means confined or limited to that application of it. However, in order that the invention may be understood it will be described in connection with the embodiment of it shown on the drawings.

In the drawings 1 and 2 generally indicate two skip hoists. The travel of one of them is greater than the travel of the other of them. In the embodiment of the invention chosen for illustration it happens that the travel of the skip hoist 1 is sub-

stantially or approximately twice the travel of the skip hoist 2, so that the travel of one skip hoist is substantially a multiple of the distance of the travel of the other but that condition need only obtain where use is made of a movable pulley 3 attached to the bucket 4 of the skip hoist 2 and through which the cable 5 fast at one end 6 and passed over a pulley 7, is reeved. The other end of the cable 5 is applied to the single driving unit 8 shown as having in the particular embodiment of the invention chosen for description but not necessarily in all cases, a single drum 9. The cable 10 of the skip hoist 1 in the present embodiment is shown as applied to the drum 9, passed over the pulley 11, and connected with the bucket 12 of the skip hoist 1. The cables 5 and 10 are so applied to the driving unit that as one is let out the other is drawn in so that when one bucket is descending the other bucket is ascending. In the particular embodiment of the invention selected for description, 13 is a track hopper having a loader 14 which supplies material to the bucket 4. a may be regarded as indicating a railway car arranged to dump into the hopper 13. In general 15 indicates equipment of some kind and including means for receiving material from the skip hoist 2 and transferring it to the bucket of the skip hoist 1. As indicated this equipment includes a hopper and chute 16, a hopper and crusher 17, and a hopper and loader 18, so that as described the embodiment of the invention chosen is adapted to receive coal at a low level, to crush or pulverize the coal at an intermediate level, and to deliver it at a high level, for example, to a conveyer 19, by which the powdered or pulverized coal is delivered for subsequent use, for example, into bins or receptacles 20.

The installation of equipment embodying the invention is economical for reasons of which the following may be mentioned: A single driving unit is required, the pit in which the hopper 13 is arranged is comparatively shallow, and the means for lifting the coal from the loader 14 to the intermediate level of the equipment 15 is simple and inexpensive. In operation there are advantages of which reference may be made to the following: It is possible to balance the bucket 12 and the bucket 4 by counter-

weighting the bucket 4, and this may be done by adding weight 21 to it or by proportioning the capacity of the buckets with respect to the weight per unit of volume of the materials handled by each. The unbalancing of the buckets may in part be due to the fact that a portion of the weight of the cable 5 is carried by the fixed support 6. Again it is possible while operating within appropriate cable speeds and with buckets of the same capacity to increase the number of trips from the lowest to the highest points, thus increasing the volume of the material handled between those points, and this is in comparison with a single skip hoist operating between the highest and the lowest point. The movable block 3 is shown as comprising a single pulley but of course it may comprise more than a single pulley in which case additional pulleys will be provided at 7. This requires no illustration or further description because it will be readily understood by those skilled in the art that the movable block 3 may be a single or multiple block. The ratio between the distances traveled by the buckets will be changed by the employment of movable blocks having different numbers of pulleys.

It will be obvious to those skilled in the art to which the invention relates that modifications may be made in matters of mere form and in construction and arrangement without departing from the spirit of the invention which is not limited as to those matters or otherwise than as the prior art and the appended claims may require.

I claim:

1. A system of the class described including a crushing plant located substantially at the ground level, a pit provided in the

ground and having arranged therein a track hopper and loader, the described location of the plant limiting the depth of the pit to the depth required by the hopper and loader, bunker provisions arranged above the ground level and crushing plant, the described location of the crushing plant minimizing the height of the bunker provisions, and two skip hoist mechanisms of which one is operative between the pit and the feed level required by the crushing plant and of which the other is operative between the discharge level of the crushing plant and the bunker provisions, whereby the drop in level at the crushing plant is excluded from the depth of the pit and the height of the bunker provisions.

2. A system of the class described including a crushing plant located substantially at the ground level, a pit provided in the ground and having arranged therein a track hopper and loader, the described location of the plant limiting the depth of the pit to the depth required by the hopper and loader, bunker provisions arranged above the ground level and crushing plant, the described location of the crushing plant minimizing the height of the bunker provisions, two skip hoist mechanisms of which one is operative between the pit and the feed level required by the crushing plant and of which the other is operative between the discharge level of the crushing plant and the bunker provisions, whereby the drop in level at the crushing plant is excluded from the depth of the pit and the height of the bunker provisions, and a single power mechanism for simultaneously operating both of the skip hoist mechanisms.

WM. P. ALEXANDER.
